Dudley M. Klein, St. Louis, Mo.

Application June 3, 1949, Serial No. 3,039

Term of patent 7 years

(Cl. D7—5)

To all whom it may concern:

Be it known that I, Dudley M. Klein, a citizen of the United States, residing in the city of St. Louis, State of Missouri, have invented a new, original, and ornamental Design for a Protector for a Skate Shoe, of which the following is a specification, reference being had to the accompanying drawing, forming a part thereof.

In the drawing:

Fig. 1 is a top plan view;
Fig. 2 is a front elevational view;
Fig. 3 is a bottom view;
Fig. 4 is a side elevational view, and
Figs. 5 and 6 are perspective views of a protector for a skate shoe, showing my new design.

I claim:

The ornamental design for a protector for a skate shoe, substantially as shown.

DUDLEY M. KLEIN.
